UNITED STATES PATENT OFFICE

2,349,467

GUTTER HANGER

Thomas L. Scott, Johnstown, Pa.

Application May 19, 1943, Serial No. 487,657

1 Claim. (Cl. 248—48.2)

This invention relates to new and useful improvements in hangers for eave troughs or gutters, the principal object being to provide a hanger which can be manufactured at less expense due to its more brief construction than present-day types of hangers now in general use.

Another important object of the invention is to provide a trough or gutter hanger wherein the usual supporting arm is fastened to the bracket in a much simpler manner than heretofore, thus saving the use of elements and also conserving time and effort on the part of labor.

Other objects and advantages of the invention will become apparent to the reader of the following description.

In the drawings:

Figure 1 is an elevational view of the assembly with the hanger in vertical section.

Figure 2 is a section taken on the line 2—2 of Figure 1.

Figure 3 is a section taken on the line 3—3 of Figure 1.

Figure 4 is an elevational view of the assembly showing the hanger in vertical section and showing a modified form of detent means.

Figure 5 is a section on the line 5—5 of Figure 4.

Figure 6 is a fragmentary rear elevational view of the upper portion of the assembly.

Referring to the drawings wherein like numerals designate like parts, it can be seen that the hanger consists broadly of two main factors, namely, a hanger 5 and a trough or gutter supporting arm 6.

More specifically, the arm 6 consists of an elongated arcuate member 7 having a down-turned outer end 8 and a hook-shaped formation 9 at its inner end. The inner end of the arm 6 has a head formation 10 formed to provide a straight edge 11 for rest against the back wall 12 of the hanger 5.

In the form of the invention shown in Figure 1, a pin is provided at the upper inner end of the arcuate member 7, this pin extending inclinedly as at 13, vertically as at 14, and then obliquely in the opposite direction as at 15.

It can be seen that the back wall 12 of the

hanger 5 has a plurality of vertically spaced openings 16 therein for receiving the pin 13 in order to support the pin against vertical movement and to hold the straight edge 11 definitely against the back wall 12.

The hanger 5 is constructed of a single piece of sheet metal, the intermediate portion of which is bent outwardly as at 17, 17 and then inwardly as at 18, 18 to the back wall 12, thus defining a channelway in which the head portion 10 of the arm 6 is seated.

The head portion 10 is preferably provided with a plurality of vertically spaced openings 19 and the inwardly and outwardly bent portions 17, 18 are likewise formed with openings 20.

Cotter keys 21 can be disposed through registering openings 19, 20, either as an additional securing means to the pin 13, or in the event the pin is left off of the arm such as in the case of 20 the arm generally referred to by reference character 6' in Figure 4. This type of arm 6' as shown in Figure 4, can be used with the same constructed hanger 5 as represented in Figure 1.

It is to be observed, that the portions 17, 17 of the hanger have side wings 22 which are apertured as at 23 to receive suitable securing means for securing the same to eaves.

While the foregoing specification sets forth the invention in specific terms, it is to be understood 30 that numerous changes in the shape, size and materials may be resorted to without departing from the spirit and scope of the invention as claimed hereinafter.

Having described the invention, what is claimed 35 as new is:

A trough hanger comprising a bracket including a vertical channel portion, an arcuate trough supporting arm having a straight inner end positioned within the channel and against the base 40 thereof, and readily detachable means between the arm and the bracket, said readily detachable means consisting in the provision of an offset pin on the inner end of the arm and having the bracket formed with an opening for receiving 45 the pin.

THOMAS L. SCOTT.
